Primary Examiner — Karen E Eldridge Powers(74) *Attorney, Agent, or Firm* — Dunlap Bennett & Ludwig PLLC; Brendan E. Squire(57) **CLAIM**

The ornamental design for a back scrubber, as shown and described.

DESCRIPTION

FIG. 1 is a rear perspective view of the back scrubber showing my new design;

FIG. 2 is a front perspective view thereof;

FIG. 3 is a rear elevation view thereof;

FIG. 4 is a top view thereof;

FIG. 5 is a bottom view thereof;

FIG. 6 is a front elevation view thereof;

FIG. 7 is a right side elevation view thereof; and,

FIG. 8 is a left side elevation view thereof.

The dash-dot-dash lines in the drawings illustrate a boundary that forms no part of the claimed design.
